UNITED STATES PATENT OFFICE.

THOMAS W. VARLEY, OF NEW YORK, N. Y., ASSIGNOR TO VARLEY DUPLEX MAGNET CO., A CORPORATION OF NEW JERSEY.

IGNITION SYSTEM.

Application filed June 1, 1928. Serial No. 282,109.

This invention relates to those ignition systems for internal combustion engines having a protective circuit which prevents the discharge of a continuous uninterrupted current 5 for any appreciable length of time.

In my copending application Serial No. 225,433 filed October 11, 1927, I have shown an ignition system in which the primary circuit includes a resistance element which may 10 be the ballast resistance and in which system I employ a time lag relay, having a time lag upon energization only, to control the continuity of the primary circuit to protect the same against a continuous drain of uninterrupted current.

In accordance with this invention I provide an ignition system which is also protected against such undue discharges, against untimely sparking, and which requires no 20 auxiliary resistance whatever in the primary circuit. For this reason my present invention is particularly well adapted to be applied to or used in conjunction with the more modern type of ignition coils which have 25 their primary windings wound exteriorly of the secondary windings and which require no ballast resistance.

As in my prior application I find it convenient to utilize what may be termed a 30 polarized time lag relay to actuate the protective circuit by controlling two pairs of contacts one pair in the primary circuit to act as a switch therein to control the continuity thereof and the other pair in a shunting circuit which shunts a winding of the ignition coil just prior to the opening of the primary circuit after a continuous uninterrupted current has flown therethrough for a predetermined length of time. In this shunting circuit I place a resistance which serves 35 the purpose of preventing a momentary short circuit across the battery as the relay functions to actuate the two pairs of contacts. I may also insert a cut-out switch in the system 40 for eliminating the protective features and allowing the ignition system to function as a normal system.

A better understanding will be had from the detailed description which follows with 45 reference to the drawings in which:

Fig. 1 is a diagram of an ignition circuit embodying my invention;

Fig. 2 is a side elevation of the relay employed;

Fig. 3 is a plan of the relay employed, and

Fig. 4 is a schematic circuit diagram of an ignition system embodying my invention and including a cut-out switch for eliminating the protective features.

As illustrated, the ignition circuit includes 60 a primary circuit and a secondary circuit the latter of which is not altered by my invention and comprises the secondary winding 1 having one end connected to the primary winding under which it is wound and the 65 other end connected by conductor 2 to the usual distributor head D which distributes the high potential current to the various plugs one being indicated at 4. The primary circuit may be said to start at the battery 5 one 70 side of which is grounded as at 6 and includes the usual manually operable switch 7, primary winding 8, shown as being wound over the secondary winding, conductor 9, terminal 10 of insulated and yieldingly mounted contact 75 bar 11 on the relay R, contact 12, contact 13 normally engaging contact 12 and carried by an insulated strip 14, said contacts serving as switch contacts, conductor 15, breaker points 16 and 17 of the timer T, and back to 80 ground at 18 thus completing the primary circuit.

The relay R may be any relay which is responsive to a continuous current but irresponsible to an interrupted current. I have 85 shown what I term a polarized time lag relay similar to that disclosed in my copending application No. 225,433 as that type relay is particularly well adapted for my purpose inasmuch as it has a time lag only upon energization and is responsive only to continuous uninterrupted current. The relay shown carries the insulated contact bar 11 which is yieldingly pulled upwardly by means of spring 20 and which carries contact 12 in position to engage contact 13 carried by the insulated strip 14, contact 13 thus limiting the upward movement of bar 11. Bar 11 also carries a contact 21 for purposes to be described. The armature 22 is hinged to the 90 core and is normally urged upwardly by means of a leaf spring 23. The armature has a contact 24 thereon directly over contact 21 which it engages on its downward movement prior to forcing the bar 11 down to open contacts 12 and 13 and opening the primary circuit.

The energizing coil of the relay is connected at one end by conductor 25 to conductor 15 at any point on the ungrounded side of the timer, and at the other end by conductor 105 110

tor 26 to the switch 7 upon the side thereof not connected to the battery thus placing the energizing coil of the relay directly across the battery through the timer whenever switch 7 and contacts 16 and 17 of the timer are closed.

In order to prevent sparking of the plugs due to an induced current in the secondary circuit, when the primary circuit is broken, 10 a circuit is provided which shunts the primary winding of the ignition coil. This circuit includes the two contacts 21 and 24 which are normally open but are closed by the action of the armature prior to the opening of contacts 12 and 13 and a resistance element 29. The circuit is as follows: One end of the primary winding 8, conductor 26, conductor 28, shown as tapped to conductor 26, resistance 29, which may be wound upon 15 20 a suitable strip secured to the relay, relay core, relay armature, contact 24, contact 21, bar 11, terminal 10 and conductor 9 to the other end of winding 8 at B. This provides an electrical shunt through resistance 29 and 25 contacts 21 and 24 across both ends of the primary winding 8, the resistance preventing a momentary short circuit across the battery, when both pairs of relay contacts are closed.

As shown in Fig. 4 I may also employ a 30 cut-out switch for eliminating the protective features entirely. For this purpose I insert a pair of switch contacts 31 and 32 in conductor 26 arranged to be bridged by a switch arm 33 which is mounted to alternately 35 bridge a second pair of contacts 34 and 35. Contacts 34 and 35 are connected by suitable wires 36 and 37 to terminals B and C. If it is desired to cut out relay R and its associated circuit, switch arm can be thrown from 40 contacts 31 and 32 to contacts 34 and 35 thus opening the relay circuit 26 and connecting terminal B directly to terminal C.

The normal operation of the system is identical with the usual modern ignition system, 45 that is, with switch 7 closed and the engine rotating so as to rotate the timer and intermittently open and close points 16 and 17, current will flow through the primary circuit, induce a current in the secondary circuit and cause sparking at the plugs. The 50 relay although having its coil permanently in circuit will not respond to the intermittent current and will not function in any respect. Should the engine stop with points 16 and 17 55 closed while the switch 7 is closed, a steady uninterrupted current will flow through the primary circuit and also through the energizing coil of the relay to which current the relay will respond. The relay then functions 60 first to close contacts 21 and 24 and establishes a shunt circuit around the primary winding of the ignition coil as follows: contact 24, armature 22, core of the relay, resistance 29, conductor 28, conductor 26, primary winding 8, conductor 9, terminal 10, 65

bar 11 and contact 21, thus eliminating the inductive action of the ignition coil. The resistance 29 serves to prevent a momentary low resistance short circuit across the battery when contacts 21 and 24 are first closed and 70 before contacts 12 and 13 are opened. Further downward movement of the armature opens contacts 12 and 13 and thus opens the primary circuit but leaves the energizing coil still connected across the battery through 75 conductor 26 and switch 7 at one end and conductors 25, 15 and points 16 and 17 on the other end.

If it is desired to omit the relay from the circuit, switch arm 33 may be rotated to 80 bridge contacts 34 and 35 thus establishing a direct circuit between terminals B and C as in the usual system without going through the relay contacts or energizing the relay and at the same time positively opening the relay 85 circuit.

Any of the present systems readily may be modified to include the features of my invention by merely making three connections, one to the battery through the switch at A, 90 one to the ignition coil at B, and one to the timer at C and by inserting a relay of the type disclosed at these connections in the manner described. For new installations the relay can be incorporated with the ignition 95 coil in one housing and no external connections need appear other than the usual terminals.

It is obvious that minor changes may be made without departing from the spirit and 100 scope of the invention as defined in the appended claims.

I claim:

1. In an ignition system, a primary circuit including a battery, an ignition coil, a 105 normally closed switch, and a timer, a relay operative to control said switch, said relay having its energizing coil permanently connected across a portion of the primary circuit, and a circuit connected across said 110 ignition coil, said circuit including a resistance element and a pair of normally open contacts actuated by said relay.

2. In an ignition system, a primary circuit including a battery, an ignition coil, a 115 normally closed switch, and a timer, a relay operative to actuate said switch, said relay having its energizing coil permanently connected across a portion of said primary current, and a circuit consisting of a resistance 120 element and a pair of normally open contacts in series connected across said ignition coil, one of said contacts being carried by the relay armature and arranged to engage the other of said contacts upon energization of said relay prior to the opening of said switch thereby.

3. In an ignition system, a primary circuit including, a battery, an ignition coil, a 125 normally closed switch, and a timer, a relay 130

- having its energizing coil permanently connected across said battery through said timer, and having its armature arranged to operate said switch, a circuit connected across the terminals of one winding of said ignition coil, said circuit including a pair of normally open contacts and a resistance element in series, said contacts being controlled by said relay.
- 5 6. In an ignition system, a primary circuit including a battery, an ignition coil, a normally closed switch, and a timer, a relay operative to control said switch, said relay having its energizing coil normally permanently connected across a portion of the primary circuit, a circuit connected across said ignition coil, said circuit including a resistance element and a pair of normally open contacts actuated by said relay, and a single cut-out switch for opening the energizing circuit of said relay and bridging said relay controlled switch. 35
- 10 7. In an ignition system, a primary circuit including a battery, an ignition coil, a normally closed switch, and a timer, a relay having its energizing coil normally permanently connected across said battery through said timer, and having its armature arranged to operate said switch, a circuit connected across the terminals of one winding of said ignition coil, said circuit including a pair of normally open contacts and a resistance element in series, said contacts being controlled by said relay, and a single cut-out switch for opening the energizing circuit of said relay and controlling a circuit shunting said resistance and said relay operated switch. 40
- 15 8. In an ignition system, a primary circuit including a battery, an ignition coil, a normally closed switch, and a timer, a polarized time lag relay operative to control said switch, said relay having its energizing coil permanently connected across a portion of said primary circuit, and a circuit connected across said ignition coil said circuit including a resistance element in series with a pair of normally open contacts actuated by 45
- 20 said relay.
9. In an ignition system, a primary circuit including, a battery, an ignition coil, a normally closed switch, and a timer, a polarized time lag relay having its energizing coil permanently connected across said battery through said timer, and having its armature arranged to operate said switch, a circuit connected across the terminals of one winding of said ignition coil, said circuit including a pair of normally open contacts and a resistance element in series, said contacts being controlled by said relay. 50
- 25 10. In an ignition system, a primary circuit including a battery, an ignition coil, a normally closed switch, and a timer, a relay having its energizing coil normally permanently connected across said battery through said timer, and having its armature arranged to operate said switch, a circuit connected across the terminals of one winding of said ignition coil, said circuit including a pair of normally open contacts and a resistance element in series, said contacts being controlled by said relay, and a single cut-out switch for opening the energizing circuit of said relay and controlling a circuit shunting said resistance and said relay operated switch. 55
- 30 11. In an ignition system, a primary circuit including a battery, an ignition coil, a normally closed switch, and a timer, a relay having its energizing coil normally permanently connected across said battery through said timer, and having its armature arranged to operate said switch, a circuit connected across the terminals of one winding of said ignition coil, said circuit including a pair of normally open contacts and a resistance element in series, said contacts being controlled by said relay. 60

In witness whereof, I hereunto subscribe my signature.
